UNITED STATES PATENT OFFICE.

RICHARD L. PARISH, OF CHICAGO, ILLINOIS, ASSIGNOR TO AMERICAN FLANGE & MANUFACTURING CO., OF CHICAGO, ILLINOIS, A CORPORATION OF ILLINOIS.

PROCESS OF MAKING CONTAINERS.

Application filed May 28, 1928. Serial No. 281,275.

My invention relates to a method of making containers and to the containers themselves which employ walls made of metallic sheet material curled into cylindrical or 5 curved shape, such containers also usually having sheet metal end walls, though the invention is not to be limited thereto.

It has hitherto been the practice to abut the ends of the metallic sheet which is curled 10 to form a cylindrical or curved container wall and to weld such abutting ends together. In carrying out my invention, I join the engaging ends of such a curled sheet by forming these ends with interleaving or 15 intermeshing continuations. This construction is not in itself leak proof wherefore I make it leak proof by providing a body or lining of sealing material between such interleaving continuations. This sealing material 20 is preferably initially liquid and is applied before the joint between the edge portions of the metallic sheet is completed. During the process of completing the joint, the body of sealing material is squeezed 25 and forced to flow into and to fill the crevices through which leakage would otherwise occur.

The invention will be more fully explained by reference to the accompanying 30 drawing in which Fig. 1 is a perspective view illustrating a drum or barrel made in accordance with the preferred embodiment of the invention; Fig. 2 is a perspective view of a portion of the drum at one stage in 35 the construction thereof, the joint between the adjacent edge portions of the curled metallic sheet being only partially formed and the body of sealing material being located in a position from which it is spread when 40 the joint is completed; Fig. 3 is a view similar to Fig. 2 illustrating the joint completed; and Fig. 4 is a sectional view on line 4—4 of Fig. 1, on a larger scale.

The container illustrated is in the form of 45 a barrel or drum of the kind which is commonly used for packaging oil. This container is composed of three sheet metal portions 1, 2 and 3. The sheet metal portion 1 is curled into a generally cylindrical shape, 50 the meeting edge portions of the sheet being margined by joint forming continuations 4 and 5. These continuations extend lengthwise of the barrel or drum and terminate at the barrel ends. The continuation 55 4 is returned to lap the wall and is spaced

apart from the wall so that it, together with the adjacent portion of the wall, is U-shaped in cross section. The continuation 5 is continued beyond the wall portion from which it springs and is U-shaped in cross 60 section to snugly receive the joint forming continuation 4, the terminating part of the continuation 5 being next the curved wall of the barrel and being snugly received between the continuation 4 and the barrel. 65 During the process of manufacture the portions 4 and 5 are initially radially disposed, the portion 5 being so much wider than the portion 4 as to fully embrace it when the formation of the joint is completed as indicated in Figs. 3 and 4.

In the stage of construction illustrated in Fig. 2, the longitudinal edge of the continuation 4 and the adjacent portion of the face of the continuation 5 that is inwardly beyond the continuation 4 form a pocket into which sealing material 6 is squirted, this sealing material being initially liquid and of such a nature as to become sufficiently hard to be held in place shortly after it is 80 applied. According to one formula, the material of which the sealing material is made may be inclusive of the following, by weight:

Per cent.	85
Ceylon crepe rubber	46.6
Precipitated calcium carbonate	46.6
Zinc oxide powder	4.7
Sulphur	1.8
Tetra methyl thiuram disulphide	.3 90

A quantity of benzol equaling the aggregate weight of the above ingredients is added thereto. The sealing material is initially liquid and is squirted upon the parts 95 4 and 5 to form a unitary structure therewith.

During the step which is taken to complete the joint from the stage shown in Fig. 2 to the final stage shown in Figs. 3 and 4, 100 the body of sealing material 6 is caused forcibly to flow into all of the crevices and spaces which intervene between the continuations 4 and 5 of the edge portions of the curved wall of the barrel, there being 105 an excessive quantity of sealing material to insure this result. As a consequence, a leak proof joint is established between the meeting edge portions of the curved wall of the barrel, this joint being permanent and suffi- 110

ciently flexible by reason of the sealing material which remains in a sufficiently plastic condition to maintain the leak proof character of the joint even though there may be 5 slight relative movements of the parts composing the joint that may arise during shipment and handling, a result which is not assured where the meeting edges of the curved wall are butt welded together. The curved 10 wall of the barrel may be formed with the usual rolling hoops 7 and may be provided with flaring circular continuations 8 which may be joined with the end walls 2 and 3 in accordance with common practice. Where 15 the flaring continuations 8 are employed, the meeting edges thereof at 9 may be effectively butt welded. By way of recapitulation, it will be observed that I have employed a method of forming curved 20 container walls which consists in curling a sheet of metal to bring opposed edges thereof in meeting relation, forming continuations upon the meeting edge portions of such 25 container wall which initially extend inwardly and are side by side and which extend along such meeting edges from end to end of the container, one of these continuations being sufficiently wider than the other 30 to be formed into U-shape in cross section when curled over the other, placing a body of sealing material upon the wider of said two continuations and at the inner longi-

tudinal edge of the other continuation, curling the wider of the two continuations over the other, and curling both continuations 35 close to the container wall and squeezing the sealing material into the spacing between and extending along the continuations.

Having thus described my invention, I 40 claim:

The process of forming curved container walls which consists in curling a sheet of metal to bring opposed edges thereof into meeting relation; forming continuations upon the meeting edge portions of such 45 container wall which initially extend inwardly and are side by side and which extend along such meeting edges from end to end of the container, one of these continuations being sufficiently wider than the other 50 to be formed into U-shape in cross section when curled over the other; placing a body of sealing material upon the wider of said two continuations and at the inner longitudinal edge of the other continuation; curling the wider of the two continuations over the other; and curling both continuations 55 close to the container wall and squeezing the sealing material into the spacing between and extending along the continuations. 60

In witness whereof, I hereunto subscribe my name.

RICHARD L. PARISH.
